PAGE 2

FIG. 3

The dominant features of my design reside in the portions illustrated in solid lines. The undisclosed side is substantially the same as the side shown.

I claim:

The ornamental design for a lift truck, as shown and described.
